UNITED STATES PATENT OFFICE.

MARION SIMPSON, OF NEWTON, MASSACHUSETTS, ASSIGNOR TO BREUKER & KESSLER COMPANY, OF PHILADELPHIA, PENNSYLVANIA, A CORPORATION OF PENNSYLVANIA.

DESIGN FOR BOX-PAPER.

No. 39,914.

Specification for Design.

Patented April 13, 1909.

Application filed December 26, 1908. Serial No. 469,490. Term of patent 3½ years.

To all whom it may concern:

Be it known that I, MARION SIMPSON, a citizen of the United States, residing at Manet Road, Newton, county of Middlesex and State of Massachusetts, have invented a new, original, and ornamental Design for Box-Paper, reference being had to the accompanying drawings for an illustration of the same.

The figure represents the design as applied to a section of the paper.

I claim:

The ornamental design for box paper as shown.

MARION SIMPSON.
